SWIMMING POOL CLEANER

Roy B. Everson, Chicago, Ill.

Application March 20, 1937, Serial No. 132,140

6 Claims. (Cl. 210--206)

My present invention relates to means for cleaning swimming pools, and similar structures, and it is especially designed to remove sediment, slime and other foreign matter that may be deposited upon the bottom or floor of these structures. In practice, my apparatus embodies a housing or head having an opening in its bottom through which an adjustable brush protrudes, said housing being adjustably supported on rollers which facilitate movement on the floor of the pool. Means are provided for removing the water and foreign matter that has become detached and agitated by the brush, and baffling devices are installed within the housing to equally distribute the flow of matter through the housing. Other means are provided to prevent inadvertent sealing of the intake aperture of the housing and to assist in the removal of sediments deposited by certain types of water.

It is the purpose of my invention to provide a device for cleaning swimming pools that has numerous objects in view among which are, compactness in the formation and disposition of the component parts; sturdiness and novelty in construction; efficiency in the performance of its required functions; facility of operation; and economy in manufacture, installation and use. I prefer to practice my invention in substantially the manner hereinafter more fully described and as particularly pointed out in the claims, reference being herein made to the accompanying drawing that forms a part of this specification.

In the drawing:

Figure 1 is a top plan of my cleaner for swimming pools.

Figure 2 is a central vertical section thereof taken longitudinally through Figure 1.

Figure 3 is a vertical transverse section thereof on line 3-3 of Figure 2.

It is to be understood that the drawing is, in a sense, merely schematic and is for the purpose of disclosing a typical or preferred embodiment of my swimming pool cleaner. In the drawing the same reference characters are used to designate like parts wherever such parts are shown in the different views.

In carrying out my invention, I employ an elongated box-like housing that is preferably a casting made from non-erosive material such as brass or other suitable metal. This housing consists of a horizontal top 5, vertical parallel sides 6 that depend from the longitudinal edges of said top, and vertical ends 7 that are connected at its top and side edges to the adjacent corresponding edges of the top and sides of the housing.

I prefer, however, to omit the bottom wall, so that the housing is a substantially U-shape in vertical transverse section as seen in Figure 3, thereby providing a relatively wide opening or mouth at its bottom of approximately the same 5 dimensions as the wall forming the top of the housing. At about the center of its length the top 5 has a discharge port 8 in the form of an integral stub that is preferably cast with the housing and is provided with facilities for coupling to it a flexible hose 9 leading to the suction side of a suitable pump 10 disposed near an outside edge of the pool where it may discharge the water and foreign matter removed from the pool 10 into a drain.

An elongated brush structure is enclosed within the housing and is disposed with the lower portion of its bristles 11 protruding out of the open bottom of the housing to an extent sufficient to engage and effectively wipe the surface upon 20 which the cleaner is moved. The back or body 12 of the brush preferably is an elongated metal bar having horizontally extended lugs 13 at its ends that fit between parallel vertical guide ribs 14 arranged in pairs on the inner faces of the ends 25 of the housing. The back or body 12 of the brush is considerably less in width than the inside width of the housing, and has a baffle plate 15 superposed thereon. This plate 15 is of such dimensions that it extends beyond and overhangs 30 the sides of the back 12, but its edges are spaced from the inner surfaces of the walls of the housing to horizontally divide the interior of the latter into upper and lower portions that communicate with each other through elongated slots or passageways 16 extending along the edges of the baffle plate 15.

I have provided suitable means for vertically adjusting the brush as well as the baffle with respect to the bottom opening of the housing, such 40 means also permitting the ready removal and replacement of the brush and the baffle plate wherever desired. To accomplish this, upstanding posts 17 are preferably anchored at their lower ends to the metal bar 12 forming the back of the 45 brush and have their upper portions extended through smooth apertures 18 in the housing top. Elongated adjusting nuts 19 of the sleeve-type are screwed down upon the threaded upper portions 20 of the posts until the bottom ends of 50 said nuts engage the outer face of the housing top. Thus, by rotating the nuts 19 in one direction or the other the brush structure is raised or lowered with respect to the bottom opening of the housing and the surface being cleared. The 55

brush and baffle plate are yieldably urged downward in the housing by coiled expansion springs 21 that surround the posts 17 between the baffle plate and the housing top and are maintained under compression by the adjusting nuts 19. By loosening and removing these adjusting nuts the brush and baffle plate may be readily removed through the bottom opening of the housing.

I have found that certain kinds of deposits upon the surface being cleaned and certain types of sediments require a special construction or nozzle on the housing in order to effectively remove such deposits and sediments. For this purpose I provide relatively flat shoes 22 of angular or substantially L-shape cross section as shown in Figure 3 that extend horizontally from the lower portions of the sides 6 of the housing. The lateral upstanding flanges of these shoes are removably attached to the housing by bolts, 20 and the free outer marginal portions of the shoes are curved or flared upward away from the bottom of the pool as shown at 23 in order to enlarge or increase the height of the intake portion of the nozzle.

25 The housing is supported above the surface being cleaned by means of rollers 24 that are preferably made of hard rubber or other suitable material to prevent marring the tiles with which pools are usually surfaced. The spindles of these 30 rollers are journaled in the pendent arms of inverted U-shaped holders 25 that are secured to adjacent ends of side-frames 26 that are disposed transversely across end portions of the housing substantially in the manner shown. Intermediate 35 their ends these side-frames are upwardly arched, as at 27, to bridge over the top of the housing and means are provided to conveniently adjust the side-frames at these arched portions with respect to the housing. Usually it is not 40 desired to have the side-frames rest directly upon the housing because of the fact that the rollers frequently wear down to small diameters which consequently lowers the housing to close proximity to the surface being cleaned. I therefore 45 interpose a plurality of shims 28 between the arched portions of the side-frames and the housing and connect all these parts together by bolts 29 that pass through openings in the side-frames, the shims and the housing top. Thus, whenever 50 the rollers become reduced in diameter, due to wear or otherwise, one or more of the shims may be removed from between the housing and the side-frames, and the parts again secured in place by the bolts. These shims are arranged in two 55 side by side stacks or piles under each side-frame, and whenever one or more pairs are removed they may be superposed upon the top of the side frame and secured in place by the bolts 29 to prevent loss. Pairs of these removed shims 60 are shown disposed upon the upper surface of the side frames as above described and are identified by the numeral 30 in Figs. 2 and 3.

It sometimes occurs that one of the rollers may accidentally break or become badly chipped due to 65 hard usage and under such conditions a corner of the housing will ordinarily drop down into engagement with the tiled surface where, if unobserved, it will scratch or otherwise mar these tiles. In order to avoid the likelihood of this damage occurring I have extended the ends 7 of the housing down below the horizontal planes of the lower edges of the sides 6 and shape these extended portions convex to provide outwardly curved skids or rockers or runners 31 that have no sharp 70 portions and will permit this portion of the

cleaner structure to glide or slide over the surface without damage to the tile. Suitable eyes 32, preferably four in number, are screwed into the sides 6 of the housing to afford facilities for removable attaching draft-chains, forked handles or other devices 33 to the cleaner structure in order that the operator outside the pool may conveniently push or pull the cleaner along the bottom surface and thereby guide it in the desired path.

When the apparatus is being used, the hose 9 is coupled to the suction side of the pump at one end and to the outlet port stub 8 at its other end, and after the draft-chains or other devices have been connected to the eyes 32 the cleaner is submerged in the pool until it rests upon the bottom thereof. When the pump is started the housing is slowly moved preferably in back and forth directions from one wall to the other wall of the pool in a regular manner, and during this movement the brush 11 agitates the sediment and wipes the deposit from the surface being cleaned below the housing while at the same time the action of the pump sucks the foreign matter and water under the shoes and 25 through the open bottom into the housing where it moves through the passageways 16 and is drawn off in the hose to be discharged by the pump into a drain. By forming the restricted 30 passageways 16 the baffle plate 15 tends to equally distribute the suction throughout the length of the opening in the bottom of the housing.

What I claim is:

1. A swimming pool cleaner comprising a submersible elongated housing provided with an inlet opening in its lower portion and having a discharge port, a brush in said housing protruding through said opening, means for adjustably and yieldably maintaining said brush in engagement with the surface upon which said housing is moved, a baffle within said housing above said brush, transversely disposed side-frames straddling end portions of said housing, rollers on said side-frames for maintaining said housing in spaced relation to the surface being cleaned, shims interposed between said side-frames and said housing, leading and trailing shoes extending laterally from lower portions of opposite longitudinal walls of said housing, skids extending below the lower edges of the housing walls, and a pipe leading from said discharge port to the suction side of a pump.

2. A swimming pool cleaner comprising an elongated housing having a longitudinal inlet opening in its bottom and provided with a discharge port, a brush carried by said housing and engaged with the surface being cleaned, elongated rigid side-frames removably disposed transversely across and bridging the ends of said housing, rollers on said side-frames supporting the housing in spaced relation to the surface being cleaned, devices for vertically adjusting said side-frames with respect to the housing, and means for removably anchoring said side-frames and said adjusting devices on said housing.

3. A swimming pool cleaner comprising an elongated box-shaped housing having an open bottom providing an inlet of substantial dimensions, a brush within said housing disposed with its lower portion protruding through said inlet, elongated rigid side-frames disposed transversely across opposite ends of said housing, rollers on said side-frames, and means for adjustably and removably mounting said side-frames on said

housing whereby to raise and lower the housing with respect to the surface being cleaned.

4. A swimming pool cleaner comprising an elongated box-shaped housing having an open bottom providing an inlet of substantial dimensions, a brush within said housing disposed with its lower portion protruding through said inlet, elongated rigid side-frames disposed transversely across opposite ends of said housing, rollers on said side-frames, means for adjustably and removably mounting said side-frames on said housing whereby to raise and lower the housing with respect to the surface being cleaned, and leading and trailing shoes of substantial width projecting horizontally from opposite sides of said housing in approximately the same plane with the housing inlet.

5. A swimming pool cleaner comprising an elongated box-shaped housing having an open bottom providing an inlet of substantial dimensions, a brush within said housing disposed with its lower portion protruding through said inlet, elongated rigid side-frames disposed transversely across opposite ends of said housing, rollers on said side-frames, means for adjustably and removably mounting said side-frames on said housing whereby to raise and lower the housing with

respect to the surface being cleaned, and downwardly curved skids at the lower edges of the end walls of said housing, which said skids extend below the horizontal plane of said housing inlet and are normally out of contact with the surface 5

6. A swimming pool cleaner comprising an elongated box-shaped housing having an open bottom providing an inlet of substantial dimensions, a brush within said housing disposed with its lower portion protruding through said inlet, elongated rigid side-frames disposed transversely across opposite ends of said housing, rollers on said side-frames, means for adjustably and removably mounting said side-frames on said housing whereby to raise and lower the housing with respect to the surface being cleaned, leading and trailing shoes of substantial width projecting horizontally from opposite sides of said housing in approximately the same plane with the housing inlet, and downwardly curved skids at the lower edges of the end walls of said housing, which said skids extend below the horizontal plane of said housing inlet and are normally out of contact with the surface being cleaned. 15 20 25
